UNITED STATES PATENT OFFICE.

EDWARD G. ROWLEY, OF BELLEVILLE, NEW JERSEY, ASSIGNOR TO UNDERWOOD TYPEWRITER COMPANY, OF NEW YORK, N. Y., A CORPORATION OF DELAWARE.

STENCILING MACHINE.

Application filed April 30, 1924. Serial No. 709,966.

To all whom it may concern:

Be it known that I, EDWARD G. ROWLEY, a citizen of the United States, residing in Belleville, in the county of Essex and State 5 of New Jersey, have invented certain new and useful Improvements in Stenciling Machines, of which the following is a specification.

This invention relates to stenciling machines, and more particularly to an ink-distributor or spreader arranged to be positioned within the cylinder of the machine, and to means for disposing of said distributor when not in use.

15 I secure within the stencil-cylinder an ink fountain which may assume the form of a cylindrical container, rotatably attached at one end to the inner end of said stencil-cylinder, and extending through the same 20 nearly to the opposite end thereof. This container is provided with one or more ink-feeding apertures or slots, from which the ink may drop upon the interior of the stencil-cylinder. The fountain is revolvably 25 shiftable upon its support, so that, after the stencil-cylinder is turned to bring any desired portion thereof to the bottom, the fountain may be turned to bring its ink-feeding apertures to the bottom.

30 One feature of the invention is the provision of means for spreading the ink evenly over the interior of the cylinder, to produce work of uniform quality.

Another feature is the provision of improved means for automatically controlling the opening and closing of the ink-feeding apertures when the container is turned to its respective operative and inoperative positions, although the device may be used 40 without this controlling means, the excess ink flowing back by gravity into the container through the apertures upon rotating back to its normal position.

The invention further contemplates the 45 provision of suitable guard-plates which function both as a shield for the brushes when in operative position and as means to prevent excess ink from flowing down and spreading over the surface of the container when the device is out of operation.

Another feature of the invention is the provision of a novel and simplified stop mechanism for limiting the angular movement of the container when rotated, and to 55 lock the same against movement during the

inking process, as well as in its inoperative position.

Other features and advantages will hereinafter appear.

In the accompanying drawings, 60

Figure 1 is a longitudinal section of a stenciling machine, showing an ink-distributor in its normal position.

Figure 2 is a longitudinal section of the ink-distributor taken on the line 2—2 of 65 Figure 4 in the direction of the arrows.

Figure 3 is a longitudinal section of the stenciling machine, showing the ink-distributor in operative position, a portion thereof being broken away to show the interior 70 mechanism.

Figure 4 is a cross-section on the line 4—4 of Figure 1.

Figure 5 is a similar cross-section, showing the ink-distributor in inking position. 75

Figure 6 is a detail view of one of the end plates of the container, showing the stop mechanism.

For the purpose of illustrating the invention, I have shown in the accompanying 80 drawings (particular reference being directed to Figure 1) my ink-distributor applied to a conventional form of stenciling machine, in which a perforated hollow cylinder or drum is covered with an ink-blanket and a 85 stencil-sheet is laid upon the blanket, the paper to be stenciled being run between the stencil-sheet and a pressure-roll, the ink being applied to the interior of the cylinder and taken up by the ink-blanket upon the 90 exterior thereof.

I have used the reference character 10 to designate a base upon which a pair of end frames 11 and 12 are mounted. A trunnion 13, secured by a set-screw 13', 95 provides a bearing upon which one end of a stencil-cylinder 14 revolves, the opposite end of the cylinder being supported in the yoke-shaped frame 11 and revolving on rollers 15 mounted in this frame. A handle 100 16 provides means whereby motion may be imparted to the cylinder.

Reference numeral 17 indicates the usual ink-blanket wrapped around the stencil-cylinder, the ends being caught upon a pair 105 of rods located in a channel member 18. An ink-container 19, comprising a cylindrical body 19' and end caps 20 and 21, is rotatably shiftable within the stencil-cylinder 14. The end caps 20 and 21 are formed with 110

flanges 20' and 21' fitting within the ends of the cylindrical body 19', and are securely fastened thereto by means of suitable screws 22, or in any other desirable manner.

A shaft 23 extends centrally through the interior of the container 19, one of the ends thereof fitting within a recess in a lug 24 formed with the end cap 20, the other end 10 of the shaft extending through a hub portion 25 of the cap 21 and a frame 26. It will be noted that the frame 26 carries an annular sleeve 27, which fits within an annular recess 27' in the hub portion 25 of the 15 end cap 21, thus providing a bearing upon which the container and its associated parts are revolvably shiftable. The shaft 23 is held against rotation through the medium of a pin 28 passing at right angles through 20 said shaft and being received within notches 28' formed in the outer end of the sleeve 27. One of a pair of cams 29 (later described) is secured upon the shaft 23 immediately adjacent the outer end of the hub 25. The 25 shaft 23, furthermore, is threaded adjacent one end and receives a nut 30 and a compression-washer 30' acting to draw the cam 29 against the outer end of the hub 25 to revolvably secure the container to the frame. 30 It will be noted that the nut 30 acts also to draw the pin 28 into the notches 28'.

One end of the trunnion 13 extends at right angles into an aperture 31 in an extension 26' of the frame 26 and is secured 35 thereto by means of set-screws 31'. Thus it will be seen that the support of the entire distributor is taken at one end of the machine, leaving the other end entirely free and accessible at all times, and that the axis of the container 19 is disposed eccentrically to the axis of the stencil-cylinder.

Ink-feeding apertures 32, disposed lengthwise in the wall of the cylindrical container 19, are normally positioned at the top of 40 said container when the device is not in use and are air-sealed by means of an automatic sealing device, which will now be described, attention being directed to Figures 2, 4 and 5.

A shaft 33 extends through the container 19, the ends being suitably supported at 34 and 34' in the end caps 20 and 21. A pair 45 of rocker-arms 35 in the form of bell-crank levers are mounted for movement upon the shaft 33 and occupy positions adjacent each of the end caps above described. Rollers 36 are carried by one of the free ends 37 of each of the rocker-arms 35 for a purpose described later. The other free ends 37 of the rocker-arms 35 are connected together by a channel bar 37' which carries a felt strip functioning as a stopper 38 to prevent air from entering the container through the ink-feeding apertures 32 when the device is 50 out of use. A spring 39 tends to normally

maintain the stopper 38 in closed position over the apertures 32, but upon shifting the container from its normal position to inking position the pair of cams 29 act upon the rollers 36 to unseat the stopper 38, as will be 55 readily understood by a consideration of Figures 4 and 5. Ink-distributing means in the form of brushes 40 are mounted radially upon the exterior of the container 19 and extend in parallelism throughout the length 60 of the apertures 32 on both sides thereof.

In order to obviate any tendency of excess ink from spreading over the exterior of the container when the same is turned up and out of use, there is provided a pair of 65 substantially right angular guard-plates 41, suitably secured upon the cylindrical body 19' and extending parallel with the brushes 40 throughout their length. When the device has been rotated to inking position the 70 guard-plates 41 act as stops to limit the degree of rotation of the stencil-cylinder during the inking operation and offer a protective shield for preventing injury to the 75 brushes.

A spring-pressed latch 42 is fulcrumed at 43 within a channel slot 44 in the trunnion 13. Stops 45 and notches 46, disposed on opposite sides in the edge of a flange 47 formed with the end cap 21, co-operate with 80 an engaging end 42' of the spring-pressed latch 42 to limit the degree of movement of the container in both directions and lock the same in a fixed position while performing the inking operation, or when out of use (see 85 Figure 2). The container receives a supply of ink through a port 48, which is closed by a screw-plug 49, and a spring-closed valve 50 may be pressed to admit air to the 90 container 19.

Operation.—Assuming the device to be in the position illustrated in Figure 1, the inking operation is performed in the following manner.

The handle of the latch 42 is pressed down, thus releasing its engaging end 42' from the notches 46, whereupon the container may be angularly shifted one-half of a revolution to a position in which the brushes 40 bear against the walls of the stencil-cylinder 14. During this inverting operation, the cams 29 have acted to unseat the stopper 38 from the inking apertures 32. In this position, the end 42' of the latch 42 has engaged the notches 46 on the opposite side of the container holding said container rigidly in place. The stencil-cylinder 14 is now rotated until a side wall of the channel member 18 comes in contact with a guard-plate 41. The spring-closed valve 50 is then pressed 110 to permit air to enter the container, relieving the vacuum tendency therein, and thus permitting a flow of ink through the apertures 32 and onto the interior of the stencil-cylinder. The stencil-cylinder is then 115

rocked back and forth through a nearly complete revolution in both directions, the guard plates 41 acting as limiting stops against the sides of the channel member 18, as will be readily apparent. This action causes the brushes to cover the interior of the cylinder with a uniform and well-distributed coating of ink.

Variations may be resorted to within the scope of the invention, and portions of the improvements may be used without others.

Having thus described my invention, I claim:

1. In a duplicating machine, the combination with a revoluble cylinder, of an ink-fountain rotatably shiftable upon its axis within said cylinder, and releasable stop means associated with said ink-fountain effective to limit the degree of angular movement thereof when shifted from one position to another position.

2. In a duplicating machine, the combination with a revoluble cylinder, of an ink-fountain arranged to be rotatably shifted upon its axis within said cylinder, and releasable stops associated with said ink-fountain effective to limit the degree of angular movement thereof when shifted in either direction.

3. In a duplicating machine, the combination with a revoluble cylinder, of an ink-fountain arranged to be shifted angularly upon its axis within said cylinder, and releasable stop mechanism associated with said ink-fountain effective to automatically secure said fountain against further movement when the same has been shifted from inoperative position to operative position, or vice versa.

4. In a duplicating machine, the combination with a revoluble cylinder, of an ink-fountain arranged to be shifted angularly upon its axis within said cylinder, said fountain including a peripheral flange having notches therein, and means acting to engage said notches, to limit the degree of angular movement of said ink-fountain when shifted from one position to another position.

5. In a duplicating machine, the combination with a revoluble cylinder, of an ink-fountain arranged to be shifted angularly upon its axis within said cylinder, said fountain including a peripheral flange having a pair of notches disposed therein 180 degrees apart, and latch means operating to engage said notches to limit the degree of angular movement of the ink-fountain from one position to a position 180 degrees removed therefrom.

6. In a duplicating machine, the combination with a revoluble cylinder, of an ink-fountain shiftable axially within said cylinder, said fountain including a peripheral flange, a pair of stops carried by the flange,

and means acting to engage said stops whereby to limit the degree of angular movement of said ink-fountain when shifted.

7. The combination with a duplicating machine, including a revoluble cylinder, of a frame secured within one end thereof, an inking device rotatably shiftable upon said frame, and means associated with said frame, co-operating with means carried by the inking device, effective to lock said inking device against movement when shifted from one of its positions to another of its positions.

8. The combination with a duplicating machine, including a revoluble cylinder, of a frame secured within one end thereof, an inking device rotatably shiftable upon its axis on said frame, a pair of diametrically oppositely-disposed stops and notches carried by said inking device, and a spring-urged latch mounted for movement in the frame, acting to engage said stops and notches to limit the degree of angular movement of the inking device and to lock the same against further movement until said latch is released.

9. In a duplicating machine, the combination with a revoluble cylinder, of an ink-fountain rotatably shiftable upon a support within said cylinder, said fountain having an ink aperture in the side wall thereof, and means effective upon shifting the fountain from operative to inoperative position, to seal said aperture from air.

10. In a duplicating machine, the combination with a revoluble cylinder, of an ink-fountain rotatably shiftable upon a support within said cylinder, said fountain having an ink aperture in the side wall thereof, and a sealing device mounted for movement adjacent said aperture effective to seal the same from air when the fountain is shifted to inoperative position, and to unseal said aperture when the fountain is shifted to operative position.

11. In a duplicating machine, the combination with a revoluble cylinder, of an ink-fountain rotatably shiftable upon a support within said cylinder, said fountain having an ink aperture in the side wall thereof, and a cam-actuated sealing device mounted for movement adjacent said aperture effective to seal the same when said ink-fountain is in inoperative position, and to unseal the aperture when the ink-fountain is shifted to operative position.

12. In a duplicating machine, the combination with a revoluble cylinder, of an ink-fountain rotatably shiftable upon a support within said cylinder, said fountain having an ink aperture in the side wall thereof, and means interior of said fountain effective upon inverting the fountain from its inking position to seal said aperture from air.

13. In a duplicating machine, the com-

- bination with a revoluble cylinder, of an ink-dispensing device rotatably shiftable upon a support within the cylinder, the axis of said ink-dispensing device being eccentric to the axis of said revoluble cylinder.
14. In a duplicating machine the combination with a revoluble cylinder, of an ink-dispensing device having an outlet opening therein, said ink-dispensing device being revolubly shiftable upon an axis eccentric to the axis of said revoluble cylinder, to cause contact of said ink-dispensing device with the cylinder wall upon a relative rotational movement of said ink-dispensing device with respect to said cylinder.
15. In a duplicating machine, the combination with a revoluble cylinder, of an ink-fountain revolubly shiftable upon a support within said cylinder, and an ink-distributing device carried by said ink-fountain effective upon shifting of said fountain to contact with the cylinder to cause distribution of ink over the surface thereof when said cylinder is rotated.
16. The combination with a revolubly shiftable ink-container having an ink-feeding aperture therein, of means to prevent spreading of excess ink over the exterior surface thereof.
17. The combination with a revolubly shiftable inking device having an outlet aperture therein, of shields adjacent said aperture acting to check the flow of excess ink over the surface of said inking device when the same is shifted to non-inking position.
18. In a duplicating machine, the combination with a revoluble cylinder, of an ink-fountain revolubly shiftable within the cylinder, and means associated with said fountain acting to limit the degree of rotation of said revoluble cylinder during an inking operation.
19. In a duplicating machine, the combination with a revoluble cylinder, of an ink-fountain rotatably shiftable upon its axis within the cylinder, and a pair of stops carried by said fountain acting when the fountain is shifted to inking position to limit the degree of rotation of said revoluble cylinder in both directions during an inking operation.
20. In a duplicating machine, the combination with a revoluble cylinder, of an ink-fountain rotatably shiftable upon its axis within said cylinder, means associated with said fountain to limit its movement beyond a predetermined position when shifted, said fountain having an outlet opening in the side wall thereof, and means to close said opening when the fountain is shifted to non-inking position.
21. In a duplicating machine, the combination with a revoluble cylinder, of an ink-fountain rotatably shiftable upon its axis within said cylinder, stops carried by said fountain, a releasable latch member arranged to engage said stops to limit the angular movement of the fountain when shifted upon its axis, said fountain having an outlet opening in the side wall thereof, a sealing device mounted for movement adjacent said outlet opening, and means to cause said sealing device to close against the outlet opening when the fountain is in non-inking position.
22. In a duplicating machine, the combination with a revoluble cylinder, of an ink-fountain rotatably shiftable upon its axis within said cylinder, stops carried by said fountain, a releasable latch member arranged to engage said stops to limit the angular movement of the fountain when shifted upon its axis, said fountain having an outlet opening in the side wall thereof, a sealing device mounted for movement adjacent said outlet opening, and means to cause said sealing device to unseal the outlet opening when the fountain is shifted to ink the interior of the cylinder.
23. In a duplicating machine, the combination with a revoluble cylinder, of an ink-fountain rotatably shiftable upon its axis within said cylinder, stop means arranged upon the exterior of the fountain, a stop-engaging member co-operating with said stop means to secure the fountain against movement when shifted to one of its positions, said fountain having an outlet opening in the side wall thereof, a sealing device mounted for movement adjacent said outlet opening, means for automatically sealing the outlet when the fountain is in non-inking position and for unsealing the outlet opening when said fountain has been shifted to inking position, the ink-distributing brushes disposed adjacent the outlet opening, and shields adjacent the brushes effective to prevent excess ink from spreading over the exterior walls of the fountain when the same has been inverted to non-inking position.

EDWARD G. ROWLEY.
